Follow Patent

X 6133

The schedule refers to in these Letters Patent and making part of the same containing a description in the words of the said

Charles Gaydon himself of his improvement in the manufacture of American wire eyes cast Buttons.

To all to whom these presents shall come. We of known that of Charles Gaydon of Waterbury in the County of New Haven in the State of Connecticut a native citizen of the United States have invented a new & useful improvement in the manufacture of American wire eyes cast Buttons & that the following is a full and exact description thereof. This invention & improvement consists ^{mainly} in the application of the cap shell ~~as~~ ^{to} inlaid work to the wire eyes cast button in the same manner in all respects except the inlaid work as they have heretofore been applied to buttons made with soldered eyes. The wire eyes cast button for coat or vest or otherwise is made stamped according to fancy burnished and edged in the usual manner & fitted to receive the cap or shell as ~~as~~ ^{is} required which is prepared from the same materials & put on & closed down in the same manner as is usually done on buttons with soldered eyes. The wire eyes cast button may be prepared for inlaid work by an indentation in the face by a suitable stamp or die or by a projection in the face of the mould or by raising the edge by stamping this die calculated for that object, when thus prepared any fancy work of brass or ornamental metal may be inserted & fixed in its place by the bursisher or by a stamp with ornamental devices impressed upon the raised edge. I do not claim any new invention in making the wire eyes cast button. This having been known before. (See no. 102000 as my first filing on this)

X (e1.33)

from the method of making a suspender, the cap, belt, or
waist or other ornaments with attached to the face of the
button as now known (and used, but does claim all my inven-
tive & improvements. The application thereof to the wire or
all button as above described for this Adolphe Stevens Pat-
ent. In testimony whereof I, George Maynard affix my name
(and seal this 6th day of October A.D. 1833.
